[57] **CLAIM**

The ornamental design for a cart for transporting collapsible tables, as shown and described.

DESCRIPTION

FIG. 1 is a perspective view of a cart for transporting collapsible tables showing my new design; FIG. 2 is a side elevational view thereof particularly illustrating the manner in which a collapsible table is carried by the cart;

FIG. 3 is a perspective view thereof on a reduced scale, illustrating the manner in which a collapsible table is loaded or unloaded from the cart; and

FIG. 4 is a top plan view thereof.
The broken line disclosure is for illustrative purposes only and forms no part of the claimed design.
